UNITED STATES PATENT OFFICE.

FREDERICK WALTER LANE, OF CHICO, CALIFORNIA.

PROJECTING INSTRUMENT.

1,142,585.

Specification of Letters Patent. Patented June 8, 1915.

Application filed July 8, 1914. Serial No. 849,699.

To all whom it may concern:

Be it known that I, FREDERICK WALTER LANE, a citizen of the United States, and a resident of Chico, in the county of Butte 5 and State of California, have invented a new and Improved Projecting Instrument, of which the following is a full, clear, and exact description.

The invention relates to drafting and its 10 object is to provide a new and improved projecting instrument more especially designed for drafting from any good pattern the true contour of the cutting edge of a knife or a cutter, such as is used in the revolving cutter head of a planer, matcher, shaper, sticker or other similar woodworking machine.

In order to accomplish the desired result use is made of two pencil holders mounted 20 to slide on the blade of a guided T-square, a guide on the blade and a connection between the said guide and the said holder to move the same in a given ratio one relative to the other.

A practical embodiment of the invention 25 is represented in the accompanying drawings forming a part of this specification, in which similar characters of reference indicate corresponding parts in all the views.

Figure 1 is a plan view of the projecting 30 instrument; Fig. 2 is a side elevation of the same; Fig. 3 is a cross section of the same on the line 3—3 of Fig. 1; Fig. 4 is an enlarged cross section of the same on the line 4—4 of Fig. 1; Fig. 5 is a section along the line 5—5 35 of Fig. 1, and Fig. 6 is a plan view of the bell crank lever used in conjunction with the guide for moving the pencil holders one relative to the other.

It is well known that the cutting edge of a 40 knife or a cutter ground to a certain pattern does not produce this pattern in the article to be cut, such as a molding when the knife is used in the usual revolving cutter head of a woodworking machine. The difference is 45 caused by the circular path made by the knife. The necessary allowance of projection over the true pattern depends upon the size of the circular path in order that the knife or cutter may produce the proper cut. 50 The amount of projection of the knife over the true pattern is not a fixed ratio or proportion. In order to produce the true contour of the cutting edge of the knife or cutter when the contour of the molding to be

produced is given is the object of the instrument presently described in detail.

On a drawing board or drawing table A is secured a track B by the use of pins B' or other fastening devices, and on the said track B is mounted to travel the head C' of a 60 T-square C having a blade C² extending over the drawing board A. The outer end of the blade C² is provided with a wheel or a caster C³ traveling on the surface of the drawing board A to hold the blade C² a 65 desired distance above the surface of the drawing table A.

On the blade C² of the T-square C are mounted to slide two holders D and E carrying pencils, tracers, pens or like marking tools F and F', of which the marking tool F is adapted to be moved along the contour G of a pattern for a molding or the like marked on a sheet of paper G' attached to the surface of the drawing board A. The 70 other marking tool F' is adapted to mark the true contour G² of the cutting edge of a knife or a cutter onto a sheet G³ attached to the surface of the drawing board A adjacent the sheet G', as plainly shown in Fig. 1. 75 The holder D is pivotally connected by a link H with one arm of a bell crank lever I fulcrumed at I' on the under side of the other holder E, and the other arm of this bell crank lever I is provided with a pin or 80 roller I² engaging a curved slot J' formed in the arm J² of a guide J adjustably secured on the blade C² of the T-square by clamping screws J³ or the like. On the top of the 85 guide J is arranged a scale K on which indicates a pointer L arranged on the holder E, the said scale representing the size of the smallest cutting circle made by the knife or cutter. Presuming, for instance, that the 90 smallest circle cut by the knife or cutter is say three inches then the user loosens the clamping screws J³ and moves the guide J lengthwise on the blade C² until the pointer L indicates on the mark "3" of the scale K, after which the guide J is clamped in place 95 by the clamping screws J³. The sheet G' containing the contour G of the molding to be produced by the cutter head is fastened to the table A and a blank sheet G³ is fastened to the table at a point below the holder E. 100 The sheet G' is so located that the marking tool F is at the smallest circle to be cut, which is indicated at the contour G (see

Fig. 1). The operator now manipulates the T-square C in such a manner that the marking tool F overlies the contour G and in doing so causes the other marking tool F' to mark the true contour G² of the cutting edge of the knife or cutter onto the sheet G³, it being understood that any sliding movement given to the holder D on the blade C² causes the holder E to slide on the blade but 10 at a ratio corresponding to the movement of the pin I² in the slot J' of the guide arms J². Thus the contour G² produced by the marking tool F' is the one to which the cutters or knives are shaped to produce a molding having the contour G shown in Fig. 1.

15 The pattern curve G has been shown in Fig. 1 in juxtaposition to the cutter curve G² to show the direction between the said curves. In practice, the curve G does not appear on 20 the sheet G³.

25 The detail construction of the T-square C is preferably as follows: The head C' is provided with a grooved wheel C⁴ mounted to travel on the track B, which latter is formed of a cylindrical rod fastened to the board A by the pins B', as previously mentioned. The blade C² of the T-square is provided at the under side with a groove C⁵ extending lengthwise of the blade to form a guide for 30 the holders D and E. The holder D (see Figs. 1, 3 and 5) consists essentially of a head made in top and bottom sections D' and D² fastened together adjacent one edge of the blade C², the section D' overlying the 35 blade C² and the section D² fitting the under side of the said blade and having a rib D³ slidably engaging the groove C⁵ (see Fig. 5) to hold the holder head slidable on the blade C². The top section D' is provided with 40 centers D⁴ on which is mounted to swing up and down an arm D⁵ extending at a right angle to the blade C² and being provided, at its free end with a suitable clamping or fastening device D⁶ for removably and adjustably holding the marking tool F in place. The pivotal end of the arm D⁵ is provided 45 with a heel D⁷ between which and the blade C² is interposed a spring D⁸ to hold the point of the marking tool F in contact with the 50 sheet G³.

55 The holder E is constructed similar to the holder D and is formed of top and bottom sections E' and E² fastened together adjacent one edge of the blade C², and the said bottom section E² is provided with a rib E³ (see Fig. 5) engaging the groove C⁵. The bottom section E² is further provided with an extension arm E⁴ on which the bell crank 60 lever I is fulcrumed. The top section E' is provided with centers E⁵ on which is mounted to swing up and down an arm E⁶ provided at its outer end with a clamping or fastening device E⁷ for adjustably and removably holding the marking tool F'. The 65 heel end of the arm E⁶ is pressed on by a

spring E⁸ to hold the point of the marking tool F' in contact with the sheet G³.

The guide J is provided with a top part J⁴ extending onto the top of the blade C² at the rear edge thereof, and to this top part J⁴ is secured the arm J² by the use of the clamping screws J³ previously mentioned. The scale K is marked on the upper surface of the top part J⁴. On loosening the clamping screws J³ the guide J can be readily adjusted 70 in a lengthwise direction on the blade C² so as to cause the pointer L to indicate at the proper mark of the scale K according to the smallest cutting circle made by the knife or cutter, as before explained.

80 Having thus described my invention, I claim as new and desire to secure by Letters Patent:

1. A drafting instrument, comprising a T-square having a blade, holders carrying marking tools slidably mounted on the said blade, a guide adjustably secured to the said blade and provided with a scale, a pointer on one of the said holders indicating on the said scale, and a connection between the said guide and the said holders to move one at a given ratio relative to the other.

2. A drafting instrument, comprising a T-square having a blade, holders carrying marking tools slidably mounted on the said blade, a guide adjustably secured to the said blade and provided with a scale, a pointer on one of the said holders indicating on the said scale, a bell crank lever fulcrumed on one of the said holders and engaging the said guide, 95 and a link connecting the said bell crank lever with the other holder.

3. A drafting instrument, comprising a T-square having a head and blade, a track for the head of the T-square to travel on, 105 holders carrying marking tools slidably mounted on the blade of the T-square, a bell crank lever fulcrumed on one holder, a link pivotally connecting the said bell crank lever with the other holder, and a guide on 110 the said blade and engaged by the said bell crank lever.

4. A drafting instrument, comprising a fixed track, a T-square having a blade and a head slidable on the said track, holders carrying marking tools mounted to slide on the said blade, a guide adjustably secured to the said blade and provided with an arm having a curved slot, a bell crank lever fulcrumed on one of the said holders and 115 engaging the said slot, and a link connecting the said bell crank lever with the other holder.

5. A drafting instrument, comprising a fixed track, a T-square having a blade and a head slidable on the said track, holders carrying marking tools mounted to slide on the said blade, a guide having a scale, said guide being adjustably secured to the said blade and provided with an arm having a 120

130

curved slot, a bell crank lever fulcrumed on one of the said holders and engaging the said slot, a link connecting the said bell crank lever to the other holder, and a pointer 5 indicating on the said scale and forming part of the holder on which the said bell crank lever is fulcrumed.

In testimony whereof I have signed my name to this specification in the presence of two subscribing witnesses.

FREDERICK WALTER LANE.
